CLAIM

The ornamental design for a string light, as shown and described.

DESCRIPTION

FIG. 1 is a perspective view of a string light showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged view of portion 8 shown in FIG. 1.

The string light is shown with symbolic breaks in its length, and the appearance of any portion of the string light between the break lines forms no part of the claimed design. The dash-dot broken lines in FIGS. 1 and 8 are for the purpose of illustrating the boundaries of the enlarged fragment shown in FIG. 8 and form no part of the claimed design.
